UNITED STATES PATENT OFFICE

118,943

DESIGN FOR A VANITY DRESSER OR SIMILAR ARTICLE

George Krick, Portland, Oreg., assignor to B. P.
John Furniture Corporation, Portland, Oreg.,
a corporation of Oregon

Application May 17, 1938, Serial No. 77,253

Term of patent 3½ years

To all whom it may concern:

Be it known that I, George Krick, a citizen of the United States and a resident of Portland, in the county of Multnomah, State of Oregon, have invented a new, original, and ornamental Design for a Vanity Dresser or Similar Article, of which the following is a specification, reference being had to the accompanying drawing, forming a part thereof.

I claim:

The ornamental design for a vanity dresser or similar article, substantially as shown.

GEORGE KRICK.
